[57] **CLAIM**

The ornamental design for a hand bandage protector, as
shown and described.

DESCRIPTION

FIG. 1 is a top plan view of a hand bandage protector
showing my new design, a hand being shown in broken
line for illustrative purposes only and forming no part of
the claimed design, this top plan view being also repre-
sentative of a bottom plan view thereof,

FIG. 2 is a front elevational view thereof,

FIG. 3 is a rear elevational view thereof,

FIG. 4 is a left side elevational view thereof,

FIG. 5 is a right side elevational view thereof.

The figures show the material of the hand bandage
protector to be an open-mesh, elastic textile material.
